UNITED STATES PATENT OFFICE.

ALFRED W. HOFFMAN, OF NEW YORK, N. Y.

TABULAR CALCULATOR.

Application filed September 22, 1925. Serial No. 57,906.

The present invention has for its principal objects the provision of a tabular calculator constructed for computation over extremely wide ranges through the medium of indicator slides arranged in a small compact casing; the provision of a calculator of this character having novel and improved calculator construction disposed within a casing; the provision of an improved form 10 of calculator unit adapted to be supported in an inclined position for service; and the provision generally of a novel and improved form of tabular calculator.

Drawings.

Figure 1 is a side elevation of an enclosed calculator casing;

Figure 2 is a side elevation thereof on a reduced scale illustrating a manner of supporting the casing;

Figure 3 is a vertical longitudinal central section through the calculator disposed in service position.

Figure 4 is a front elevation thereof illustrating the manner of employing the calculator elements;

Figure 5 is a transverse section on the line 5—5 of Figure 7;

Figure 6 is a fragmentary sectional view 30 through the casing top and attached cover therefor taken on the line 6—6 of Figure 1;

Figure 7 is a perspective illustration of one of the calculator slides employed;

Figure 8 is a perspective of a computation card for disposition in the slide;

Figure 9 is a perspective view of the transparent cover member for the computation card;

Figure 10 is a fragmentary vertical section 40 through a modified form of calculator slide holder;

Figure 11 is a sectional view on the line 11—11 of Figure 10;

Figure 12 is a fragmentary section 45 through a slide holder illustrating a modified form thereof;

Figure 13 is a similar view of another modified form of holder;

Figure 14 is a similar view of still another modified form of holder;

Figure 15 is a similar illustration of a further modified form of holder;

Figure 16 is a top plan view of the con-

struction illustrated in Figure 12 with the slide holder being shown in section. 55

Description.

Details of the invention comprise a casing formed of spaced parallel side walls 20 connected by a transversely extending flat 60 bottom 21 disposed parallel with an open top of the casing. The side walls 20 are further connected by an inclined rear wall 22 having an out-turned flange 23 formed on its upper edge and provided intermediate 65 its ends with laterally extending edge flanges 24 at each side edge thereof. The casing is further provided with a flat foot section 25 formed on the front edge of the bottom 21 and disposed at an angle thereto 70 between the side walls of the casing. The outer end of the foot section 25 connects with the rearwardly inclined front wall 26 of the casing which is bent backward upon itself at its upper end to form the inwardly 75 extending section 27 having at its lower terminal an upwardly inclined shelf 28 extending in parallel relation to the bottom 21.

At the open top of the casing the side 80 walls 20 are provided with out-turned laterally extending edge flanges 29 extending the longitudinal length thereof and adapted for engagement by the inturned edge flanges 30 of a flat cover plate 31 adapted to be slid 85 over the top of the casing from the rear in locking engagement with the flanges 29. The cover plate 31 is formed of a metal blank having its rear portion bent upon itself at a right angle to provide the leg 90 extension 32 having an inwardly inclined terminal flange 33 at its end.

Disposed within the casing slightly beneath the top thereof is an inclined rack 95 for holding the computing slides of the calculator. This rack is formed of side plates 34 extending adjacent to and parallel with the side walls 20 of the casing being transversely connected by parallel spaced top and bottom plates 35 and 36 respectively. The front edge of the rack is supported upon the shelf 28 formed on the front wall 26 of the casing as best illustrated in Figure 3, while the rear end 37 is seated upon the upper edge of the rear wall 22 of the casing being retained in position by means of 100 105

a keeper 38 formed of an angle metal blank having at opposite ends of the inner section thereof upstanding ears 39 in pivotal connection with the casing walls 20 by means 5 of the eyelets 40. By the pivotal connection of the keeper with the casing walls, the rear end 37 of the calculator rack is retained upon the top of the rear wall of the casing underneath the inner section of the 10 keeper. The forward end of the calculator rack is anchored in position on the shelf 28 by means of a flanged keeper plate 41 having at opposite ends upstanding ears 42 pivoted to the side walls 20 of the casing by 15 means of the eyelets 43, the flange 44 whereof is adapted to engage over the upper edge of the front wall 26 of the casing to dispose the plate 41 at right angles to the top plate 35 of the rack with its edge engaging the 20 top of the rack retaining same against accidental withdrawal from within the casing. It will be apparent that upon rocking the keeper 38 upon its pivot 40 that it will swing rearwardly of the casing to clear the 25 rear edge of the rack. Likewise the front keeper 41 may be rocked upon its pivot to dispose the body thereof flatly against the front wall of the casing whereby the rack may be lifted as a unit from within the 30 casing.

The spaced top and bottom plates 35 and 36 respectively of the calculator rack are provided with a staggered series of transversely extending rectangular apertures 45 35 which receive therethrough the calculator slides generally indicated at 46 in Figure 4. Each of the calculator slides, in the preferred form of the invention, comprises a substantially rectangular metal blank 47 40 having its side edges inturned to provide the spaced flanges 48. The top of each slide is provided with a tab section 49 terminating in an upstanding lifting knob 50, the tab section below the knob being provided 45 with a struck out shoulder 51, which shoulder extends oppositely to a transversely alined pair of outstruck shoulders 52 arranged in the body of the slide adjacent the lower end thereof. At the lower 50 end of each slide the body thereof is provided with a centrally disposed out-struck shoulder 53 extending rearwardly of the slide in the direction of the shoulder 51, and at each side edge the body of the slide is 55 extended to provide the legs 54. The computation card 55 illustrated in Figure 8 is disposed within the slide beneath the edge flanges 48 being retained therein by the transparent cover plate 56 also engaged beneath the edge flanges 48 of the slide. The bottom edges of the computation card and its cover plate are supported upon the shoulders 52 thus providing a unitary computing element formed of the slide card and cover 60 plate. As illustrated in Figures 3 and 4, 65

the normal position of the slides 47 in the calculator rack is in lowered position with the shoulder 51 of each slide engaging the top plate 35 of the rack leaving only the upper end or tab portions of the slides 70 visible through the open top of the casing.

The normal inoperative position of the casing is shown in Figure 1 with the cover in applied position. When it is desired to employ the calculator in the working out of some problem, the cover plate 31 is removed from the casing and may be inserted beneath the bottom 21 in the position illustrated in Figure 2 with the leg 32 elevating the rear of the casing to impart a forward 80 inclination thereof. Another, and more permanent service position of the calculator is illustrated in Figures 3 and 4 wherein the cover plate after removal is disposed in supporting engagement with the rear wall of the casing, with the edge flanges 24 being received under the edge flanges 30 of the cover plate. In this position of the parts the upper edge of the cover plate engages under the out-turned flange 23 at 85 the top of the rear wall of the casing elevating the casing into a forwardly inclined position with the front of the casing resting upon the flat foot section 25, the leg extension 32 of the cover plate lying flat 90 to provide in conjunction with the foot portion 25 a stable support for service position of the calculator. In this position of the parts it will be observed that the rack containing the calculator slides is disposed in 95 a forwardly inclined position bringing the slides into a substantially upright position whereby they may be easily manipulated through the casing top. When any particular slide is desired to be employed its knob 100 50 is grasped and the slide is drawn upwardly through the rack until the curved shoulder 53 at the lower edge of the slide engages the bottom plate 36 of the rack. This engagement forces the body 47 of the 105 slide forwardly, and causes the lower ends 57 of the edge flanges 48 of the slide to engage over the upper face of the bottom plate 36 of the rack whereby the slide will be self supporting in elevated position. In 110 lowering the slide it is merely necessary to rock the same slightly forward to clear the engagement of the flange ends 57 whereupon the slide will drop into its normal position.

In the modified form shown in Figure 115 10 the calculator rack 58 is provided with a stepped bottom plate 59 arranged in a spaced relation therefrom approximating the major portion of a slide length. In this modification of the invention the slides 120 60 are in all practical respects identical with the slides of the preferred form with the exception that the back of each slide is provided with a central longitudinal out-struck rib 61 which bears against the edge 125

of the rack apertures 45 to provide for a frictional engagement by a slide spring tension between the top plate 58 of the rack and the slide at all points. In this form 5 as the slide is elevated, due to the frictional engagement as described it can be disposed in any position as it will automatically be retained therein until forcibly retracted within the rack.

10 The modification illustrated in Figures 12 and 16 consists in the provision of a bowed spring 62 arranged within the slot formed in the rack plate 63 for engagement against the slide 64, which slide is provided at its

15 lower end with a stop shoulder 65. In this modification the bowed spring 62 is secured in position by means of an attaching flange 66 fastened to the rack plate 63 by means of the securing elements 67.

20 In the modification illustrated in Figure 13 a leaf spring 68 having one end 69 anchored in a rack plate 70, is extended within the slide aperture for frictional engagement against the calculator slide 71. In the modified form illustrated in Figure 14 the rack plate 72 is provided with a strip of rubber or felt 73 arranged in the slide receiving slots for frictional engagement with the calculator slide 74. In the modification illus-

25 trated in Figure 15 the top plate 75 of the rack is provided with spring fingers 76 formed by down turning the edges of the plate adjacent the slots through which the calculator slides 77 are disposed. In all of the modified forms of the invention as described, 30 means are provided for frictionally binding the computator slides against some portion of the rack for retaining the slides in any position in which they may be placed.

35 40 As illustrated in Figure 4 the computation cards 55 are arranged with left hand unit columns adjacent amount columns wherein the amount adjacent each unit indicates the result of multiplication of the particular unit by rate number given on the top of the tab which in this particular instance is .0434.

Beneath the rate number the indicating number of the particular card is disposed, which in the present instance is 1 indicating that the units of the cards run from 1 to 10. It 50 will be apparent that the person desiring to work out some problem involving the multiplication of some unit or fraction thereof by some particular unit or fraction of unit, 55 may find the particular card whose index number shows that the number to be multiplied is to be found thereon, together with the rate, and elevates the card to extended position in the rack. By running down the columns of figures the desired answer may 60 be found at once and the card replaced. It is obvious that the use of this small and compact tabular calculator enables a great saving of time, as all parts are quickly and 65 easily accessible for operation.

While in the particular instances given the calculations are made upon the basis of multiplication it is to be understood that the invention is equally applicable to addition, subtraction, division, or the working out of 70 any mathematical problems from predetermined calculations, and the calculator is not limited to the use as described.

Claims:—

1. In a calculator, a support, an inclined 75 plate carried thereby, said plate having a series of spaced slots formed therein, a plurality of metal blanks slidably disposed through said slots, and coacting means on said plate and blanks, for retaining said 80 blanks in elevated or retracted position relative to said plate.

2. In a calculator, a support, an inclined plate carried by said support, said plate having a series of spaced slots formed therein, 85 a plurality of metal blanks slidably disposed through said slots, and resilient spring fingers carried by said plate and bearing against said blanks for retaining said blanks in elevated or retracted position relative to 90 said plate.
